WEAVING OF TEXTILE FABRICS

William W. Dennison, West Englewood, N. J., and Chester C. Abramson, Lavale, and Walter E. Davis, Cumberland, Md., assignors to Celanese Corporation of America, New York, N. Y., a corporation of Delaware

Application April 18, 1951, Serial No. 221,652

1 Claim. (Cl. 139—316)

1

This invention relates to the weaving of textile fabrics and relates more particularly to a novel process and apparatus for the weaving of textile fabrics substantially free from set marks.

In the weaving of textile fabrics, the looms on which such fabrics are being woven are frequently stopped either by the loom operator or through the action of the various stop motions with which such looms are normally equipped to prevent the production of defective fabrics. After correcting whatever conditions necessitated the stopping of the looms, the said looms are started again by the operator to continue the weaving of the textile fabrics. The stopping and starting of the looms produces noticeable marks on the woven textile fabrics, which marks are commonly called stop marks or set marks. While these set marks are not too noticeable in certain types of woven textile fabrics and therefore do not greatly affect their commercial value, they are very noticeable and therefore highly objectionable in other types of woven textile fabrics and the presence of more than a very small number of these set marks in a piece of these latter types of woven textile fabrics leads to the downgrading of said fabrics.

It is an important object of this invention to provide a novel process and apparatus for the production of woven textile fabrics which will be free from the foregoing and other difficulties and which will be especially efficient in operation and simple in construction.

A further object of this invention is to provide a process and apparatus for the production of woven textile fabrics substantially free from set marks.

Other objects of this invention, together with certain details of construction and combinations of parts, will be apparent from the following detailed description and claim.

It has been discovered that when a loom is stopped, the tension on the warp yarns that have not yet been woven into the textile fabric tends to remove some of the crimp from the warp yarns in that portion of fabric positioned between the breast beam over which the textile fabric passes on its way to the take-up roll, and the fell of the fabric, i. e. the edge of the fabric which is closest to the reed of the loom. When the loom is started up after having been stopped, the first few picks are over-beaten into the fabric resulting in a tight set mark. Moving of the fell of the fabric to the position it occupied before the loom was stopped does not successfully eliminate the set marks although it does reduce their noticeability in some types of fabrics.

2

It has been found that substantially to eliminate all traces of a set mark the fell of the fabric must be moved, before the loom on which said fabric is being woven is again started, to a position closer to the reed of the loom than the position it occupied when the loom was stopped. The precise position to which the fell of the woven textile fabric must be moved before starting the loom will depend upon the nature of textile fabric being woven and of the loom employed in the weaving operation. However, in the weaving of many different types of textile fabrics on several different types of looms, the set marks have been substantially eliminated from said fabrics by moving the fell of the fabric, before again starting a loom once it has been stopped, to a position from about 0.060 to 0.090 inch closer to the reed of the loom than the position it occupied before the loom was stopped; the exact distance for any type of fabric being readily determined by the loom operator. The fell of the fabric may be positioned at any desired point by rotating the pick wheel of the loom, as is well understood in the art.

Any suitable measuring means may be employed accurately to determine the position the fell of the fabric after the loom has stopped and before it is again started, which measuring means may, for example, be optical, electrical or mechanical in nature. Optical means have been found to be especially well suited for this purpose since they enable the fell of the fabric to be magnified to any desired extent so that its position may be determined accurately with a minimum of difficulty. The optical means may comprise a suitable magnifier or microscope mounted to view the fell of the fabric, or an optical projector suitably positioned to cast an image of the fell of the fabric onto a screen. In positioning the fell of the fabric before the loom is started, more reproducible and more accurate results are obtained if the measurement of said position is made, not on the last pick in the fabric, but on the pick next adjacent thereto.

While the positioning of the fell of the fabric in the manner described above will substantially eliminate the set marks from the fabric, it has been discovered that the appearance of the fabric may be improved even further if the tension is removed from the fabric and the warp of yarns when the loom is stopped and the tension is not again applied to the fabric and the warp of yarns until the loom is about to be started. Advantageously, the loom is provided with means which will automatically remove the tension from the fabric and warp of yards when the loom is

3

stopped without the necessity for special action on the part of the loom operator. For example, means may be provided to release the pawl on the pick wheel when the loom is stopped thereby effectively removing the tension on the fabric and the warp of yarns. In this case, the loom may also be provided with braking means which will automatically engage the pick wheel when the pawl is disengaged therefrom to limit the speed of rotation of said pick wheel and to prevent overrunning of the fabric roll to which said pick wheel is secured.

A preferred embodiment of the apparatus of this invention is shown in the accompanying drawings wherein:

Fig. 1 is a diagrammatic side elevational view of the loom,

Fig. 2 is a detail view, on an enlarged scale, of a portion of the loom shown in Fig. 1,

Fig. 3 is a plan view, on an enlarged scale, of a portion of the loom shown in Fig. 1,

Fig. 4 is a detail cross-sectional view, on an enlarged scale, taken along the line 4—4 in Fig. 3 in the direction of the arrows, and

Fig. 5 is a showing of the field of the microscope when the fell of the fabric is positioned properly.

Referring now to the drawings, the reference numeral 11 designates a warp beam from which a warp of yarns 12 is drawn under suitable tension over a whip roll 13 which is usually loaded by means of springs, weights, or the like (not shown). From the whip roll 13, the warp yarns 12 are passed through a stop motion device 14 and are then threaded between lease rods 15 to separate the yarns into two groups. After leaving the lease rods 15, the warp yarns 12 pass through harnesses 16 which raise and lower selected yarns in any desired sequence to form a shed 17. Positioned in front of the harnesses 16 is a lay or batten 18 which carries a raceplate 19 and is provided with a reed 21 between the dents of which the warp yarns 12 are threaded. A shuttle 22, riding on the raceplate 19 and guided by the reed 21, passes through the shed 17 to lay a filling yarn or pick 23 into the said shed. After the shuttle 22 has passed through the shed 17, the batten 18 is moved from the position shown in full lines to the position shown in dotted lines in Fig. 1 of the drawings to beat the pick 23 into its proper position in fabric 24, the fell of which is indicated by reference numeral 25. The fabric 24 then passes over a breast beam 26, around a positively driven sand roll or take-up roll 27, over a guide roll 28 and is wound onto a fabric roll or cloth roll 29. There is provided in the loom a ratchet wheel or pick wheel 30 equipped with a pawl 31, which pick wheel is connected through suitable means (not shown) to the take-up roll 27 and the cloth roll 29 and is driven stepwise in synchronism with the operation of the loom to take up the fabric at the rate it is produced. It is to be understood that the construction and operation of the loom described above is entirely conventional.

When the loom is stopped, either through the operation of the stop motion device 14 or in any other manner, brake arm 32 of the loom will drop from the position shown in full lines to the position shown in dotted lines in Fig. 2 of the drawings and shipper arm 33 of the loom will rotate clockwise about pivot 34 on which it is mounted, all in a manner well known in the art. The rotation of the shipper arm 33 will carry rod 35, which is secured to the shipper arm 33 by means of a bracket 36, into contact with the

4

pawl 31, releasing the said pawl from engagement with the pick wheel 30 and thereby effectively removing the tension from the fabric 24 and the warp yarns 12. To limit the speed of rotation of the pick wheel 30 and prevent overrunning of the cloth roll 29 when the pawl 31 is released, the brake arm 32 is provided with a bracket 37 carrying a brake member 38 which will frictionally engage pick hand wheel 39 fastened to the pick wheel 30 when the brake arm 32 drops on the stopping of the loom.

To position properly the fell 25 of the fabric 24 before the loom is again started after it has been stopped, there is provided a measuring means, indicated generally by reference numeral 41. The measuring means 41 comprises a plate 42 fastened to the breast beam 26, which plate 42 has an arm 43 secured thereto by means of a hinge 44. The arm 43 carries a bracket arm 45 which extends over the fabric 24 and supports an adjustable mount, indicated generally by reference numeral 46, carrying a microscope 47. The mount 46 comprises a lower slide 48 which is fastened to the bracket arm 45 and has a stud 49 projecting upwardly therefrom. An upper slide 51 having a slot 52 extending therethrough is positioned adjustably on the lower slide 48 and is held against movement by means of a knurled nut 53 in threaded engagement with the stud 49. Fastened to the upper slide 52 is a fitting 54 which carries the microscope 47 and is provided with an adjusting rod 55 to enable the microscope 47 to be focused sharply on the fabric 24.

In starting the loom after it has once been stopped, the measuring means 41 is moved manually to the position shown in Fig. 3 of the drawings. The pick hand wheel 39 is then rotated by the loom operator to apply tension to the warp yarns 12 and the fabric 24 and to draw the fell 25 of said fabric 24 under the microscope 47 until the pick 23, which is next adjacent to the fell 25, is aligned with the index line 56 as shown in Fig. 5 of the drawings. In this position, the fell 25 is closer to the reed 21 than it was when the loom was stopped. The measuring means 41 is then pivoted about the hinge 44 to the position shown in dotted lines in Fig. 1 of the drawings so that it will not interfere with the operation of the loom and the loom is again started. If the index line 56 is positioned properly, which may be readily effected by shifting the upper slide 51 to one side or the other along the length of the fabric 24, there will be no set mark in the woven fabric.

It is to be understood that the foregoing detailed description is given merely by way of illustration and that many variations may be made therein without departing from the spirit of our invention.

Having described our invention, what we desire to secure by Letters Patent is:

In a process for the weaving of textile fabrics on a loom wherein the loom is stopped and started again during the weaving operation, the steps of substantially eliminating set marks from the woven textile fabric, which comprises removing tension from the fabric and the warp of yarns when the loom is stopped, whereby due to the release of tension, the fell of the fabric moves towards the reed of the loom, applying tension to the fabric to move the fell thereof in a direction away from the reed to a different position which is between the position occupied by the fell of the fabric after said release of tension and the position occupied by the fell of the fabric

when the loom was stopped, said different position being about 0.060 to 0.090 inch from the position occupied by the fell of the fabric when the loom was stopped, and then starting the loom when the fell of the fabric is in said different position.
